UNITED STATES PATENT OFFICE.

LOUIS L. BENTLEY, OF BEAVER FALLS, PENNSYLVANIA, ASSIGNOR TO ARMSTRONG CORK COMPANY, OF PITTSBURGH, PENNSYLVANIA, A CORPORATION OF PENNSYLVANIA.

METHOD OF MAKING ARTIFICIAL CORK.

Application filed June 15, 1921, Serial No. 477,747. Renewed February 19, 1926.

My invention has relation to the treatment of artificial cork, and more particularly to the manufacture of shaped bodies from cork particles or granules.

It has been common practice heretofore to make cork bodies of the character above stated by compressing the cork particles in suitable molds, and then placing the molds in a baking oven and subjecting them to heat while retaining the cork mass under compression. It has also been proposed to effect the heating of the cork by the use of super-heated steam; and in the co-pending application filed by Leonard W. Bertelsen, Jr., Serial No. 477,748 there is described and claimed a method of using steam for this purpose in which the steam is passed through the mass of compressed cork.

I have discovered that a more efficient action may be obtained by the use of a heating medium of a nature to cause a chemical reaction on the cork, this reaction being of a character to materially increase the temperature in the mass under treatment, above the temperature of the heating medium used. I am not prepared at this time to fully state the nature of this exothermic reaction, but it is of an oxidizing character; and the medium employed should contain sufficient oxygen to produce such a reaction. The medium which I have heretofore employed with good results, is hot air, although furnace gases, or a mixture of air and steam may be employed. I have obtained good results by using heated air of a temperature of from 220° to 310° C. supplying from 35 to 40 cubic feet per minute of such air to each square foot of area of the cork mass being treated. Usually from 30 to 35 minutes is required for the treatment. The mass is then allowed to cool in the mold.

In the accompanying drawing I have shown one form of apparatus which may be employed in carrying out my invention. In this drawing the numeral 2 designates a mold body into which the mass of cork to be treated is compressed and by which it is shaped. The mass is held under compression between the perforated bottom plate 3 and the perforated top plate 4 by any suitable means, such as the keys 5. These perforated top and bottom plates are preferably of two thicknesses, having perforations of different sizes. The hot air or furnace gases,

or the mixture of air and steam is supplied from any suitable source by means of a pipe 6 terminating in a funnel 7 which forms a seat for a flange 8 on the lower end of the mold body, a packing or gasket 9 being interposed between the two flanges. The mold body also has the perforated internal flange 10 forming a support for the bottom mold plate. The hot gases escaping from the mass may pass into the open air or they may be collected by a removable inverted top funnel 11 having an offtake pipe 12. If desired, this pipe 12 may be connected with a fan which will return the air and gases to a heater in which they can be re-heated and then supplied under pressure to the bottom funnel for re-use. In some instances, this is advisable, as such regenerated air and gases contain less oxygen than does atmospheric air, and a less strong reaction occurs within the cork mass.

I have proven the fact of the reaction by inserting temperature measuring means at different portions of the cork mass during the operation. These tests have shown that the temperature of the mass increases from the bottom upwardly, final temperatures being reached which are considerably greater than the temperature of the heating medium upon its entrance into the cork mass.

The completion of the operation can be determined by temperature measuring devices inserted in the mass, or by observing the color and character of the escaping gases.

My invention provides a practical commercial method of making shaped artificial cork bodies with comparatively small expense. The time required to effect a treatment is very much shorter than the old operation of baking in ovens. It is also shorter than the time required to effect the treatment by the use of super-heated steam. Furthermore, the reaction which is produced within the cork is extremely effective in causing the expansion and binding of the particles together, the result being a shaped body which possesses a considerable degree of homogeneity and which has considerable structural strength.

I do not limit myself to the use of any particular apparatus for carrying out my invention, as it is obvious that it may be carried out by the use of various forms of apparatus.

The time required for the operation may be somewhat shortened by pre-heating the cork particles, but this I do not ordinarily consider advantageous, as it requires a separate partial-heating operation.

I claim:

1. The herein described method of treating cork particles which consists in passing through a mass of such particles while held under applied compression independently of any heating medium, a heating medium of a character which will produce an exothermic reaction within the cork mass, substantially as described.
2. The herein described method of treating cork particles which consists in applying pressure to the same in a mold, and passing therethrough while under compression a heating medium of a nature to cause an exothermic reaction to take place within the mass of cork particles, substantially as described.
3. The herein described method of forming shaped artificial cork bodies which consists in passing a heated oxygen-containing medium through a mass of cork particles while held under applied compression by a mold, substantially as described.
4. The herein described method of forming shaped artificial cork bodies which consists in passing a heated oxygen-containing medium through a pre-compressed mass of cork particles, substantially as described.
5. The herein described method of forming shaped bodies of artificial cork which consists in charging a mass of cork particles into a shaping receptacle, separately compressing the particles therein, holding the compressed mass under compression, and

passing a heating medium therethrough of a character which will produce a heat reaction within the mass, substantially as described.

6. The herein described method of making shaped artificial cork bodies which consists in initially compressing a mass of cork particles in a shaping receptacle, and passing hot air through the mass while holding it under such applied compression, substantially as described.

7. The herein described method of making shaped artificial cork bodies which consists in compressing a mass of cork particles in a shaping receptacle, passing hot air through the mass while holding it under compression, removing the air and gases escaping from the mass, reheating the same, and re-using the same in the further treatment of the same or of similar cork masses, substantially as described.

8. The herein described method of making shaped artificial cork bodies, which consists in preheating a mass of cork particles, compressing the preheated particles in a suitable mold, and thereafter passing an oxygen-containing heating medium through the mass while it is still under compression, substantially as described.

9. The herein described method of making shaped artificial cork bodies, which consists in preheating a mass of cork particles, compressing the preheated particles in a suitable mold, and thereafter passing hot air through the mass while it is still under compression, substantially as described.

In testimony whereof, I have hereunto set my hand.

LOUIS L. BENTLEY.
